TYPEWRITING MACHINE

William F. Helmond, West Hartford, Conn., assignor to Underwood Elliott Fisher Company, New York, N. Y., a corporation of Delaware

Application September 14, 1937, Serial No. 163,739

10 Claims. (Cl. 197—74)

This invention relates to typewriting machines of the standard or heavy duty type, and more particularly to case-shifting mechanisms effective by shifting the type-bar basket, and to improvements in the mounting and guiding means for the type-basket and case-shifting stops therefore, to render the machine comparatively quiet in operation.

The invention aims to increase the operating efficiency of the typewriter by providing a case-shift mechanism operable with a minimum of effort on the part of the operator, the mechanism being so arranged in relation to the type-bar segment that the operator need exert only a slight pressure on the shift-key to control the raising and lowering of the segment in case-shifting, the invention also providing an improved case-shift stop affording dependable means for accurately positioning the upper and lower type relative to the platen, the case-shift mechanism and stop both co-operating to bring the segment to either position without imparting noise or impact to the machine.

The invention provides a case-shift mechanism operable to lower the normally raised type basket, the mechanism including a pair of toggles operating in tandem at each end of the segment, the arms of which being in substantial alignment hold the type basket in normally raised position and which, upon being actuated by either the shift-lever or the shift-lock lever are caused to fold, thereby lowering the type-bar assembly, against the gradually increasing tension of a co-operating return spring.

The shift-lock lever, operating either in unison with, or independent of the shift-lever, has connected thereto, the mentioned return spring, the same being of adequate power to cause the toggle mechanism to return to normal aligned condition, thereby raising the type basket to its normal position; the effort of the operator being only that required to release a stop pawl by depressing the shift-lever, the operator thereafter serving only to control the raising of the type basket by allowing the shift-key to rise by power of the return-spring. The same ease of operation is had in effecting the case-shifting by means of the non-locking shift-key, it being noted that the work of raising the type basket is accomplished by the return-spring and toggles, the respective shift-keys serving merely to control the operation.

To suspend the type basket in a floating or buoyant manner, the basket is subjected to the tension of a pair of balance-springs which are

suspended from a fixed portion of the machine and have their lower ends engaging the basket at suitable points.

A further feature of the case-shift mechanism, comprising a system of shift-keys and shift-lock keys at each side of the machine, resides in the provision of a rock-shaft which serves to coordinate each set of keys in operation by operably joining the two toggle mechanisms, corresponding arms of the respective toggles being fixed to the rock-shaft to act in unison although the control of the basket-shift be effected only on the shift-key at one side of the machine.

Certain advantages are had in conjunction with the case-shift mechanism of the invention by providing a case-shift stop of novel construction affording limiting means for the travel of the type-bar segment or basket operable in a soft, quiet manner to gradually and positively arrest the motion of the basket without causing any shock or noise in the machine. The case-shift stops each comprise a pad of laminations or sheets, preferably metallic, the laminations being mounted in cantilever manner to project directly from a fixed bracket upon which each pad of laminations is clamping held. This clamping of the laminations so compresses the pad at the region of attachment to the bracket, that the extending portions of the laminae are caused to diverge from each other so as to provide minute cushioning air spaces between the respective laminae. The two outside laminae or leaves are fabricated of spring steel, while the intermediate leaves are constructed of a relatively inert or soft material, such as soft iron. Thus, as a member, the basket or platen, during case-shifting, moves into engagement with one of the projecting flared pads, the adjacent spring leaf is gradually sprung into engagement with the succeeding leaf, the second with the third and so forth, until the entire pad is compacted to a solid stop during which time the air between each leaf is slowly expelled to afford the cushioning action and mute any noise otherwise had.

Obviously the stop-pads offer resistance to compaction and the toggle mechanism affords a means whereby the laminae are easily compactable by a light force, such as the said key return-spring, under advantage of greatly increased leverage at the time when the laminae are being compacted. Explaining it differently, the case shift member is movable by the toggle mechanism at greatly varying leverage, which leverage is relatively small or inferior during the major part of the case-shift movements and which le-

verage is relatively superior, during the restoration of the case-shift member to normal-case position while the stop-pad is being compacted.

The cantilever portion of each laminated pad 5 is backed by an adjustable screw, threadedly carried in a bracket extending from the machine and affords means by which the position of the type-bar segment, in either extremity of case-shift motion, may be determined with accuracy, it being 10 noted that the projecting portion of each pad, being cantilever, may be flexed to the desired stopping position.

The means for mounting and guiding the type-bar segment in case-shift movement, embodies 15 other features of the invention. The type-bar segment includes a frame which journals the mentioned rock-shaft, which shaft, extending laterally toward side-plates of the machine, is provided with anti-friction rollers which function 20 both as slid able journals for the rock-shaft, as well as guiding means for the segment in case-shifting, each roller tracking on edges of a slot in the side plate of the machine.

The upper portion of the type-bar segment is 25 guided for case-shifting movement on a pair of ball-guide units at each end of the segment, each having a single ball therein, the ball races of each unit presenting novel arrangements to afford accurate adjustment of the guide units as well as 30 smooth frictionless action in their guiding function. An outside ball race is adjustably carried on a side plate of the machine, being movably positioned thereon by a bolt extending from the race through the supporting member and having 35 a wedge plate disposed between the ball race and the support, the positioning of which accurately effects the desired adjustment. When the desired adjustment is determined, same may be secured by tightening a nut on the race bolt to 40 clamp the wedge plate.

The complementary ball races of each ball-guide unit are each carried on and adjacent opposite ends of the type-bar segment. Each of these races presents an elongate plate of resilient material secured at one end to a pad of the type-bar segment so that a substantial length of the plate overhangs the pad in cantilever manner to yieldably engage the corresponding ball. One of these cantilever ball races is preferably backed 45 at its free end by a boss extending from the segment-frame to contact the back of the race, the other cantilever ball race being substantially unsupported at its free end in that an adjacent boss on the segment frame is spaced slightly 50 therefrom. This spacing is at a minimum so as to back the resilient ball race against any undue flexure which might result in momentary excessive looseness to the opposite ball-guide unit. The resilient mounting of at least one of the 55 segment ball races presents an arrangement whereby a constant pressure is applied to the races and balls of each guide unit and serves to limit the combined pressure on the ball races such as may be applied in adjusting the outer 60 race, the amount of space between the cantilever race and the segment boss being an accurate indication of the extent to which the race is being flexed at the time of adjustment. The uniformity of the pressure thus assures a smooth action of 65 the guide units in supporting the segment in case-shifting movement.

Another feature of the invention, in conjunction with the case-shifting mechanism, is the novel arrangement of the shift-lock pawl to 70 operate with both the shift-lock lever and the

shift-lever in such manner as to facilitate locking and release of the case shift. The pawl is pivotally mounted on the lock-lever and is extended laterally in a lug to engage a portion of the shift-lever, suitable spring means being provided to hold the pawl lug in constant engagement with the lock-lever member, the mentioned spring serving also to urge the pawl into locking engagement with an adjustably stationary stop on the machine. Thus it will be seen that during 10 depression of the lock-lever in case-shifting, the locked pawl is coercively released to locking position actuated by its spring to swing during which movement, the pawl lug maintaining constant engagement with the shift-lever member, holds 15 the shift-lever constantly but yieldably in normal raised position.

In releasing the case-shift lock by depression of the shift-lever, the reverse action takes place. The member of the shift-lever, engaging the lug 20 of the locked pawl, gradually swings the pawl to disengage its stop and at the instant of release, a lug projecting from the shift-lever and overlying a portion of the lock-lever, engages the latter to receive the load of the type-bar basket therefrom so that the return of the case-shifting movement is controlled by the manual upward release of the shift-lever to check the effect of the return spring in actually raising the basket. 25

Other features and advantages will hereinafter 30 appear.

In the accompanying drawings:

Figure 1 is a transverse sectional view through the machine embodying the invention, taken on a front and back medial plane and showing the 35 type-bar segment in normal upper position for printing the lower type case.

Figure 2 is a fragmentary end elevational view of the type-bar-segment frame.

Figure 3 is a front elevational view taken on a 40 plane transverse of the machine just forward of the type-bar segment, portions thereof being shown in section.

Figure 4 is a detail perspective view of a wedge 45 plate forming part of the segment-frame mounting and guiding means.

Figure 5 is a fragmentary horizontal section through the segment frame illustrating the 50 guide bearings mounting the segment for case-shift movement.

Figure 6 is a perspective view of the entire 55 case-shift mechanism in normal position, with the type-bar segment normally raised for lower-case printing.

Figures 7 and 8 are fragmentary perspective 60 views illustrating the two operating positions of the case-shift mechanism; the type-bar segment having been lowered for upper-case printing; Figure 7 illustrating the mechanism at the completion of down-shift to lock the setting by depressing the shift-lock key, and Figure 8 showing the mechanism operating to temporarily lower the segment for momentary upper-case printing by depressing the shift lever. 65

Figure 9 is a transverse sectional view through 70 the group of laminations forming the case-shift stop.

Figure 10 is an enlarged detail view looking at the side of the case-shift stop.

Figure 11 is an enlarged front elevation of the 75 case-shift stop, including the associated toggle and rock-shaft, and

Figure 12 illustrates in perspective the corresponding cantilever raceways of the segment mount.

The type-action illustrated in the drawings is similar to that shown and described in applicant's Patent No. 2,072,878 and dated March 9, 1937. The type-action includes a system of key-levers 12, fulcrumed adjacent the back of the machine, the key-levers being flexibly joined by links 13 to a series of sub-levers 14 pivoted on a fulcrum-rod 15, carried in a cross-bar 16 mounted on the side plates 17 comprising the frame of the machine. The sub-levers 14 actuate a system of type-bars 18 by means of pull-rods 19 flexibly joining the free end of each sub-lever 14 to a drive arm 20 of the type-bar 18. The series of type-bars 18 are pivotally mounted in a segment 21 for swinging toward a common printing point on a platen 22, the latter being guided for letter-space movement, by a platen-carriage 23 riding in a trackway 24 extending between the side plates 17. The segment 21 is mounted and guided for case-shift movement as shown more clearly in Figures 1, 2 and 3, the segment 21 being secured to a segment-frame 25, having depending members or arms 26 each forming at their free ends bearings 27 in which a rock-shaft 28 is journaled, the shaft 28 extending laterally to the side plates 17 of the machine and carrying rollers 29 at the ends thereof.

As will be hereinafter described in further detail, the rock-shaft 28 accomplishes several functions, namely, that of co-ordinating the action of the two units of case-shift operating levers at the sides of the machine, and guiding the lower portion of the segment-frame during case shifting, portions of the rock-shaft 28 also engaging the case-shift stops to limit the travel of the segment 21. The ends of the rock-shaft carry rollers 29 which track in slots 30 in the respective side-plates 17.

The upper portion of the segment-frame 25 is mounted and guided for case-shift movement in a pair of anti-friction bearing units 31, 32 at the respective lateral extremities of the segment frame. Each bearing unit includes a single ball or roller 33 jointly affording slight pivotal movement for the segment on the common axis defined by the respective rollers 33, as may be required in aligning both the upper and lower guide-means of the segment to compensate for slight variations in manufacture. Each bearing unit 31, 32 includes resilient raceway plates or leaves 34, mounted in cantilever manner on the segment-frame 25, each being secured to a pad 35 offset from the frame. Each raceway plate 34 extends upwardly from its mounting to afford yieldable engagement with the roller 33, which rides in a raceway 36 therein. The projected portion of one of the raceway plates 34 is backed by an abutment or boss 37 for fixed support thereon, the other raceway plate 34 having a similar abutment 38, disposed to back the projected portion of the same, but spaced slightly therefrom as indicated at 49 to permit limited flexure of the plate 34. The space 49 being very slight, practically obviates any lateral play or disalignment of the segment 21, although affording a sufficient latitude for flexure of the plate 34 to provide such yieldability as will assure smooth action of the bearings 31, 32 during case shifting. The plates being resilient exert constant pressure on the rollers 33 so that they are always in tight rolling contact and therefore do not drop. The yieldable raceway plate 34 may be offset angularly at a desired degree, Figure 12, so as to impart the desired

pressure to the bearings upon being flexed to straight condition at assembly.

The respective bearing units 31, 32, are each provided with complementary raceways 39 mounted on the main frame of the machine by means of brackets 40 extending from the trackway 24 to assure accurate disposition of the segment 21 and platen 22. Each raceway 39 includes a threaded stud 41 extending through the bracket and having a nut 42 thereon securing the raceway. At least one of the raceways 39 is adjustably positioned so as to regulate the pressure between the raceways and rollers of the bearings 31, 32 and particularly to so flex the raceway plate 34 of bearing 32 toward the abutment 38 to assure the desired minimum spacing 49 therebetween. The bracket 40 of bearing unit 31 has its surface adjacent the raceway 39 bevelled to accommodate a wedge-plate 43 between same and the raceway 39, the wedge-plate 43 being U-shaped so as to straddle the stud 41. Simultaneous adjustment of the bearing units 31, 32 is afforded by the loosening of the nut 42, and thereafter driving the wedge-plate 43 upward to loosen, or downward to tighten the bearings until the desired pressure is attained, after which the nut 42 is turned up to secure the adjustment by clamping the wedge plate 43 tightly in place.

A member of the segment frame 25, preferably the projecting portions of the rock-shaft 28, moves in a path confined by a pair of case-shift stops 44, shown more clearly in Figures 10 and 11, to limit the travel of the segment 21 in a quiet manner during case shifting. A bracket 45 provides anchorage for a pair of co-extensive laminated pads 46 which project therefrom in cantilever manner into the path of the rock-shaft 28. The bracket 45 is secured to the main-frame side-plate 17 and is formed in an open loop to present opposed walls against which the respective pads 46 are clamping held. The medial portion of bracket 45 has integrally formed thereon oppositely projecting prongs 47, corresponding pairs of which align the several laminae of the pads 46, the latter being preferably clamped to the bracket 45 as by a bolt 48 passing therethrough. The bolt 48, during assembling, is so tightened as to compress the anchored portions of the pad laminae 46, to cause the projecting portions to be slightly flared from each other, thereby affording minute air spaces or voids between the respective laminations of the pad. As shown in Figure 9, the two outer laminae or leaves are fabricated of a resilient material such as spring steel to withstand repeated impact and flexure and thus sustain the intermediate leaves which are preferably fabricated of a relatively inert material such as soft iron. It has been found that, by composing a stop of a plurality of members, same is more effective in cushioning impact as in case-shifting and deadening any noise which may result, particularly wherein most of the stop elements are made of an inert material. The sound deadening or muting effect is further augmented by the flared arrangement of the stop leaves, which, upon being impacted or engaged by the segment member during case-shifting, are gradually packed or compressed one against the other so as to expel the air from between the leaves. The resilient outer leaf engageable by the shaft 28 is of such slight strength as to flex readily when pressed without causing the slightest bounce or rebound to the segment.

The projecting pads 46, in addition to affording a cushioning stop for the segment, also facilitate

adjustment so that the upper and lower stop positions of the segment may be positively determined to accurately locate both type cases relative to the printing line on the platen, each pad 46 being backed at its projecting end by an adjustment screw 50 abutting same. The screws 50 are threadedly carried in lugs 51 overlying the pads 46, the lugs 51 being formed on a bracket 52 secured to the side plate 17.

10 The structure and operation of the case-shift mechanism, Figures 1, 6, 7 and 8, will now be described, the same functioning to lower the normally raised segment against the power of spring means, and inversely to permit return to raised position of the segment actuated by the spring means, by operation of the proper control keys. As aforeindicated, the rockable shaft 28, being rotatably carried on the segment-frame 25, embodies means by which the control of the shift-keys is imparted to the segment in case-shifting. At each extremity, the rockable shaft 28 has associated therewith an articulated leverage-train 55, comprising a first arm 56 affixed to the shaft 28, and a second arm 57 fulcrumed at 58 on the main frame, and articulated to the first arm 56, so as to constitute a toggle joint. The fulcrum 58 comprises a rotatable eccentric bushing, Figure 11, carried on a bracket of the side plate 17 by a stud 58¹ by which the effective axis of the fulcrum may be adjusted to compensate for wear in the toggle-joint 55 or for other purposes. Fulcrum 58 is disposed on a line defining the path of travel of the segment-frame 25 in case-shifting and below same, so that when the arms 56 and 57 are aligned, one with the other, the segment 21 and associated type-bars 18 are maintained in raised position thereby. As arm 57 is caused to swing, the toggle-joint or leverage-train 55 is unlocked and folded to permit lowering of the segment assembly.

15 The rotation of arm 57 is controlled by operation of one of the shiftkeys, a return spring 59 acting always to restore the mechanism to normal with the segment raised. The arm 57 has a drive arm 57¹ extending angularly therefrom, flexibly joined by a link 60 to an arm 61 of a shift-lock lever 62. Shift-lock lever 62 is fulcrumed on the sub-lever fulcrum-rod 15 and extends forwardly of the machine, terminating in a shift-lock key 63. A similar shift-lock lever 62 is provided at each side of the machine, the same being operably connected to a corresponding toggle 55 by its link 60. Each shift-lock lever has associated therewith a shift-lever 64, also fulcrumed on rod 15 and carrying a shift-key 65 at its free end. Shift-lever 64 includes a lug 66 extending therefrom to overlie the lever 62 so that upon depressing the shift-lever 64, the lock-lever will move therewith, although the shift-lock lever 62 may be actuated independently of the shift-lever 64. The return spring 59 is anchored on the machine, its end being joined to a depending member of the lock-lever arm 61 whereby to urge the toggles 55 to aligned condition so that same hold the segment raised, the toggles 55 being stopped at aligned setting by the engagement of the lock-lever 62 with a guide-plate 74 or other member of the machine.

20 It will be noted from the foregoing that the rockable shaft 28, by operatively connecting the arms 56, functions to coordinate the actions of both of the toggles 55 whereby lowering or raising power thereof is imparted equally to both extremities of segment 21, Figure 6. Since each toggle 55 is operably associated with a corresponding

shift-lock lever 62, the actions of the respective levers 62 are also coordinated. The rockable shaft 28, connecting the two arms 56 of the toggles 55 together, is rotatably carried in the segment-frame 25, at a relatively high elevation in the machine, thereby affording adequate space underneath for mechanisms such as the rearwardly extending key-levers.

25 A shift-lock 67 is provided to lock lever 62 down, the lock 67 being so associated with the respective shift-levers 62, 64, that when both levers move in unison, as by depressing lever 61, the lock is ineffective, and inversely, as the shift-lock lever 62 moves independently of the shift-lever 64, the lock 67 is allowed to engage. Lock 67 comprises 10 a lock pawl 68 presenting a bell-crank pivotally mounted on the lock lever 62 and urged by a spring 69 to swing into locking engagement with a detent 70, but normally prevented from so doing by the engagement of a lateral lug 71 of pawl 68, 20 with a pad 72 on the shift-lever 64.

25 Figure 7 illustrates the operation of the mechanism in locking the segment down by depressing the lock-lever 62, the lock pawl 68 having been allowed to swing into engagement with the detent 70 by the tendency of the lug 71 to move away from the pad 72, thereby releasing the pawl 68 to permit its spring 69 to actuate the pawl into engagement with the detent 70. This action is due to the relative positions of the lock-lever 62 30 and the shift-lever 64 which, during depression of the lock-lever 62, are moved apart and consequently release the pawl 68 to engage the detent.

35 In releasing the lock 67, the reverse operation takes place, the lock being released by depressing 35 the shift-lever 64 during which its pad 72, engaging the lateral lug 71, swings the pawl 68 free of the detent 70, the pawl releasing at the instant the lug 66 reaches the depressed lock-lever 62. The shift-lever 64 thus assumes the power of 40 the return spring 59, the latter tending to raise the segment 21, Figure 8. Shift-lever 64 is now permitted to rise, being manually controlled, and the segment 21 returns to its normal raised position.

45 A particular advantage of the novel case-shift lock 67 is that both the shift-lock key 63 and the shift-key 65 are at a constant elevation at the time the function of either is required. As is usual in case-shift mechanisms, the shift-lock key is locked down during the interval at which the segment is locked down for upper-case printing, but, in such machines the shift-key is also lowered. In the present invention the shift-key 50 55 65 remains at normal position although the shift-lock key 63 is depressed and the operator may therefore accustom herself to finding the shift-key 65 at the same elevation at all times. Furthermore, the work of releasing the pawl 68 from its detent 70 is minimized since the releasing is effected during the entire down-stroke of the shift-lever 64. This improved operation makes for an appreciably light touch and smooth action of the shift-lever 64 in its unlocking function, the same acting without jar, by assuming the load of the segment mass, effective by the return spring 59, at the instant of release of lock 67.

55 The respective actions of each shift-lever 64 are co-ordinated by a rockable bail 75 trunnioned on brackets 16 adjustably affixed to the guide-plate 74 by screws 77 disposed in slots therein. The rockable bail 75, extending laterally of the machine, includes a forked arm 78 at each end thereof which engages a pin 79 car- 70 75

ried on a member 80 of the shift-lever 64. It will be noted that the detent 70, co-operating with the lock 67, forms part of the bracket 76, so that both the detent and the journal of the bail 75 are adjustable simultaneously. In the event that lowering of detent 70 is required in regulating the shift mechanism, the lower locked position of lever 62 necessitates a greater drop for shift-lever 64 to release the lock 67, which increase is accommodated by lowering the bracket 76.

The work of the return springs 59, in restoring the type-bar segment 21 to normally raised position in co-operation with the toggles 55, is supplemented by balancing springs 82 which have the effect of resiliently sustaining the segment 21. Springs 82 are anchored at their upper ends to a fixed portion of the machine and are secured to studs 83 projecting from the segment-frame 25, Figures 3 and 6. The balance springs 82 may be so tensioned as to yieldably sustain the entire mass of the type-bar basket, the weight of which is supported by the segment-frame 25, the effect being to substantially reduce the effort required to move the segment in case-shifting.

The letter-feed escapement-mechanism illustrated is similar to that used in the standard noiseless Underwood machines except that certain changes are embodied therein, to adapt the mechanism for association with the other improvements shown. The escapement-mechanism, Figure 2, comprises an arcuate universal bar 91, arranged on the segment 21 for engagement by a heel 92 of each type-bar 18 which, during swinging, engages the universal bar 91 to actuate the letter-feed escapement. The universal bar 91 includes side arms 93 pivoted to a rock-frame 94 journaled at 95 in brackets 96 extending rearwardly from the segment 21. The rock-frame 94 co-operates with a tongue 97 of the universal bar for sliding motion relative to the segment 21. A link 98, flexibly connected to the rock-frame 94, threadedly carries adjustable collars 99 engageable with a dog rocker 100 through which the link 98 projects. The dog rocker 100 is pivoted for rocking motion at 101 on a bracket 109 hung from the carriage guide-frame 24 and has a member 102 extending forwardly and carrying at its free end a spring-backed pawl 103 and a stop-dog 104, each engageable with an escapement-wheel 105. The escapement-wheel 105 is rotated coaxially with the endwise travel of the platen-carriage 23, wheel 105 being carried on a shaft 106 including a pinion 107 in mesh with a gear rack 108 on the carriage 23.

In inactive position, the pawl 103 holds the platen-carriage 23 stationary against the power of its travel spring, not shown, the pawl 103 being normally engaged in the teeth of the escapement-wheel 105. As the type-bar heel 92 strikes the universal bar 91, the link 98 is pulled by action of the rock-frame 94 and the dog-rocker member 102 is oscillated so that the pawl 103 moves free of the wheel 105, allowing the latter to rotate an amount equivalent to one letter-space, the rotation of wheel 105 being limited by the action of stop dog 104 which, being pivotally mounted, swings a limited degree while engaged by wheel 105 to stop same at the completion of a letter spacing. As the type-bar 18 drops back, the dog-rocker 101 is restored by a spring 110. Pawl 103 is returned to normal po-

sition engaging the tooth of wheel 105 being released by dog 104. Pawl 103 is pivoted to permit return of the platen carriage to the right, pawl 103 ratcheting over wheel 105, now rotating reversely. The letter-feed mechanism may also be operable by a spacer-key in the usual manner.

Referring to the provision of shift-key mechanism at each side of the machine, it will be noted that at the depression of either shift-lock lever 62 relatively to its companion shift-lever 64, the other shift-lock lever 62 is also depressed relatively to its companion shift-lever 64, since both of said levers 62 are operatively connected by means of the cross-shaft 28. Hence both of the locking pawls 67 are caused to move to effective position under their detents 70, as in Figure 7, at the depression of either shift-lock lever 62. The depression of either shift-lever 64 for the purpose of releasing the companion locking pawl 67 also serves, by means of the cross-shaft 75, to depress the other shift-lever 64 thereby to release also the locking pawl 67 associated with the latter.

It will be seen that in the restoration of the parts to normal (lower-case) position the compacting of the upper laminated stop-pads 46 against the stop-screws 50 is effected by the force of the restoring springs 59. Said spring force may be small, and hence the springs 59 may be light, since said springs work through the mechanical-leverage-increasing toggles 55 to squeeze and compact the upper stop-pads 46. In lowering the shift-frame 25 to upper-case typing position by depressing the case-shift keys 35 a light finger-pressure upon said keys avails to compact the lower laminated stop-pads 46 against the stop screws 50. Thus, case-shifting may be effected by a light, easy finger-touch upon the case-shift keys.

In typewriting machines it is of utmost importance to accurately arrest the case shifting body or member, so that all characters whether of the lower or upper case variety will be printed in exact alignment. The laminated stop pads 46 herein employed prevent all possible overthrow of the shiftable member by their full compaction to a solid non-yielding final stop. The toggles 55 when being straightened squeeze said laminations to full compaction in lower case typing position so that the shifting segment will be accurately located relative to the frame and the printing point. The return spring-power to drive the segment to normal case position at the release of the shift key need be but very light because of the leverage-increasing toggle device that squeezes the laminations to a solid pack. The return springs 59 are also effective to lock and retain said toggles 55 in straightened position to retain the segment against the tendency of the laminae to separate. Since the return spring 59 may be extremely light, it follows that the key touch to shift the segment to upper case position is also extremely light.

Variations may be resorted to within the scope of the invention, and portions of the improvements may be used without others.

Having thus described my invention, I claim:

1. In a typewriter, having a main frame and a member mounted for movement from either of two case-positions to the other, stop-pad means comprising slightly spaced laminae arranged to be solidly compacted against said frame by the movement of said member to at least one case position, said laminae offering resistance to com-

paction and serving to noiselessly arrest and locate said member, and means for moving said member from either one of said case-positions to the other, the last said means including devices effective during at least one of said movements for providing greatly increased leverage while compacting the laminae.

2. In a typewriting machine, having a main frame and a member mounted for movement from either of two case-positions to the other, stop-pad means comprising slightly spaced laminae arranged to be compacted against said frame by the movement of said member to at least one case-position, said laminae offering resistance to compaction and serving to noiselessly arrest and locate said member, and means for moving said member to either case-position, said means including devices adapted to assume a dead center position in moving said member to at least one case-position to thereby move said member at increased leverage while compacting said laminae and provide for the locking of said member.

3. A typewriting machine as set forth in claim 2, comprising, means for varying the position to which said member is movable by movement of said devices to said dead center position.

4. In a typewriting machine, having a main frame and a member mounted for movement from either of two case-positions to the other, stop-pad means comprising slightly spaced laminae arranged to be compacted against said frame by the movement of said member to at least one case-position, said laminae offering resistance to compaction and serving to noiselessly arrest and locate said member, and means comprising a toggle-linkage, pivotally connected with said member and said frame for moving said member to either case-position, and adapted to assume a straight-line position in moving said member to at least one case-position to thereby move said member at increased leverage while compacting said laminae and to provide for the locking of said member.

5. A typewriting machine as set forth in claim 4, comprising, means for varying the position to which said toggle-linkage is able to move said member in assuming said straight-line position.

6. In a typewriter having a main frame and a member mounted for movement from either of two case-positions to the other, stop-pad means comprising superposed elongate leaves of hard resilient material extending from a support and relatively spaced in a stop region, to stop said member in its movement to at least one of said case-positions, by being compacted against said frame, said leaves offering considerable resistance to compaction and serving in being compacted to noiselessly arrest and locate said member, and means for moving said member from either one of said case-positions to the other at greatly varying leverage which is relatively small during the major part of said case-shift movements, and relatively vastly superior, during at least one of said case-shift movements while compacting said leaves against the said resistance.

7. In a typewriter having a main frame and a member mounted for movement from either of two case-positions to the other, stop-pad means comprising spaced laminae arranged to be compacted against said frame by the movement of said member to either case-position, said laminae offering resistance to compaction, and serving to noiselessly arrest and locate said member, a case-shift key, a spring, and member-moving means operable by said key to move said

member to one case-position and by said spring, at the release of said key, to move said member to the other case-position, comprising, a leverage changing device, providing for inferior leverage movement of said member by said spring during a major part of the shift-movement and for vastly superior leverage movement of said member by said spring while said laminae are being compacted.

8. In a typewriter having a main frame and a member mounted for movement from either of two case-positions to the other, stop-pad means comprising spaced laminae arranged to be compacted against said frame by the movement of said member to either case-position, said laminae offering considerable resistance to compaction and serving in being compacted to noiselessly arrest and locate said member, a case-shift key, a spring, and member-moving means operable by said key to move said member to one case-position and by said spring, at the release of said key, to move said member to the other case-position, comprising, a toggle device linked to said frame and said member to assume respectively a broken-line position in being moved to said one case-position and a straight-line position in being moved by said spring to the said other case-position, whereby said spring operates under advantage of greatly increased leverage while said laminae are being compacted against said frame and whereby said member will be locked against movement, except by operation of said key.

9. In a typewriter, having a main frame and a member mounted for movement from either of two case positions to the other, means to stop said member in said case-positions, including, an upper-case and a lower-case stop on the frame associated respectively with an upper-case and a lower-case stop on said member, a plurality of superposed, inherently spaced, hard leaves interposed between said associated stops, the said leaves providing cushions that are compactable between the stops to noiselessly, yet positively arrest said member, means to individually adjust one of every two associated stops toward or away from the other, and means for moving said member from either of said two case-positions to the other, the last said means including devices effective during at least one of said case-shift movements for providing greatly increased leverage while compacting the leaves between the effective stops.

10. In a typewriter, having a main frame and a member mounted for movement from either one of two case-positions to the other, at least one stop-pad for limiting each one of the said case-shift movements, said stop-pads comprising superposed leaves of hard resilient material shackled to the frame near a stopping-region and inherently slightly spaced relative to each other at the said stopping region, a back-stop for each one of the said pads, adjacent the said stopping region, on the said frame, means to individually adjust the said back-stops, the leaves of the said pads being adapted to noiselessly and positively arrest the said member in being compacted against the said back-stops, and means for moving the said member from either one of said case-positions to the other, the last said means including devices effective during at least one of said case-shift movements for providing greatly increased leverage while compacting the leaves.
